UNITED STATES PATENT OFFICE

WILLIAM EARL HUGHES, OF CHICAGO, ILLINOIS, ASSIGNOR TO SULLIVAN MACHINERY COMPANY, A CORPORATION OF MASSACHUSETTS

AUTOMATIC COMPRESSOR CONTROL SYSTEM

Application filed May 1, 1930. Serial No. 448,991.

This invention relates generally to an improved automatic control system for prime mover operated mechanisms and more particularly to an improved automatic control system for pumping mechanisms driven by a synchronous motor.

An object of my invention is to provide an improved automatic control system wherein a driving motor for a pumping mechanism, 10 herein a fluid compressor, is adapted to operate continuously irrespective of whether the compressor is connected to or disconnected from the prime mover. Another object is to provide an improved system where- 15 by a relatively close pressure regulation of the receiver pressure may be obtained. A more specific object in this respect is to provide an improved automatic control system having a plurality of compressor units driven 20 from a common motor preferably of the synchronous motor type. Another object is to provide an improved system and control circuit whereby the current for the control circuit may be supplied from the main line only 25 after the driving motor is synchronized onto the line. A still further object is to provide improved control means whereby a compressor may be automatically shut down in accordance with abnormal operating condi- 30 tions such as excessive temperatures of the bearings or of the compressor discharge fluid. Still another object of the invention is to provide improved means whereby this last function may be obtained without interfer- 35 ing with the operation of the motor; while a still further object in this respect is to provide improved means whereby the complete installation including the motor may be shut down in case of abnormal operating condi- 40 tions existing in connection with the motor, such for instance as excessive temperatures, created for example in the motor bearings, although this temperature control could be extended to any other part of the motor such 45 as its windings. Still another and more specific object is to provide an improved push button start and/or stop control for the synchronous motor.

Other objects and advantages of my invention will more readily be understood by per-

sons skilled in the art, from the following description and the accompanying drawings, in which,—

Fig. 1 is an end elevation of the driving motor and a plurality of compressor units 55 driven thereby; and

Fig. 2 is a wiring diagram of the control mechanism and circuits, mechanical elements of which are illustrated in a conventional manner merely for purposes of illustration. 60

In the illustrative embodiment of my invention there is shown for purposes of illustration a prime mover, preferably a synchronous motor, adapted to drive either or both of two compressors constituting what is herein referred to as units A and B. It is very desirable to be able to operate a synchronous motor continuously, so as to maintain a high power factor, or to improve the same, but it is necessary, in order to maintain a substantially close range of receiver pressure, to load and unload the compressors, and in accordance with economy of operation it is also desirable to shut down either or both of the compressors in accordance with the demand 70 for pressure fluid. In my improved system I have provided improved means and control circuits whereby a compressor may be unloaded when a predetermined receiver pressure is obtained but still continue to be driven for a predetermined interval of time, but thereafter be disconnected from the synchronous motor which continues to operate. In order to obtain the very best operating conditions both as to maintaining a relatively 80 close receiver pressure range and also tend to smooth out the load on the driving motor, the two compressor units, which may be either compound or single stage units, are so controlled that one unit operates between cer- 85 tain pressure limits and the other unit between other limits, with the two pressure ranges sufficiently overlapping whereby at certain times when the demand is large both 90 may be operated.

To accomplish the above and other functions the common synchronous driving motor 1, for the two compressor units A and B, is supplied with alternating current from lines L_1 , L_2 , and L_3 . To start operation of 100

the equipment, a momentary contact push button switch 2, which is normally open, is closed, whereby current flows from line L_3 through wire 3, switch 2, wire 4, contact 5, 5 solenoid coil 6 and wire 6a back to main line L_2 . Energization of solenoid 6 closes two sets of contacts as by contact bars 9 and 10 constituting an armature. The contact bar 9 completes a holding circuit for the solenoid 10 6 to permit release of push button 2, this circuit comprising wires 3, 11, normally closed stop push button switch 12, wire 13, contact bar 9 and fixed contact 5 to solenoid 6, wire 6a to line L_2 . Current now flows from wire 15 3 through wires 11, 13, bar 10, contact 14, wires 15 and 16, through normally closed temperature control relay switches 17, solenoid coil 18 and through wire 8 back to main line L_1 . Energization of coil 18 closes switch 20 19 whereupon current then flows from wire 3 through wires 11, 13, 15, normally closed overload relay switch 22, wire 23, switch 19, a wire 24 to energize the main line switch solenoid 25, from which the current flows to 25 wire 8 back to the main line L_1 . Upon energization of the solenoid 25, the main line switch 26 is closed, thereby setting up a rotating magnetic field in the windings 27 of the synchronous motor 1. As is well understood, the motor may be brought up to synchronous speed by the use of suitable means such as amortisseur windings and synchronized onto the line by suitable relay controls for connecting the exciter to the direct 30 current field when the rotor has reached synchronous speed. A similar arrangement has been previously described in detail in an application of Sanford filed November 16, 1927, Serial No. 233,695, now matured into 35 Patent No. 1,785,980, patented Dec. 23, 1930. This synchronizing control is effected in that as soon as the main line switch 26 is closed the revolving magnetic field induces an alternating current, in the motor field coils 28, 40 which flows through a closed circuit by way of wires 29, 30, normally closed switch 31, wire 32, resistance 34, coil 36 and wire 37 to the other side of the field as by wire 38. This induced current continues as long as there is 45 relative movement between the field coils and the revolving magnetic field, the frequency of this current gradually diminishing as the rotor approaches synchronous speed. The effect of current in this circuit is to 50 energize the coil 36 and oppose the closing of switch 39. However, when the rotor attains or sufficiently approaches synchronous speed, this current automatically dies out sufficiently to allow coil 40, which is energized after the main line switch 26 is closed as by wires 41, 42, wire 44 and wire 8 to L_1 , to close the switch 39. Assuming now that the rotor has reached synchronous speed, switch 39 is closed under the influence of coil 40 and the circuit is thus established

through coil 43 by way of wires 3, 7, 46, coil 43, wire 45, switch 39, wires 44 and 8 between lines L_3 and L_1 . Energization of coil 43 automatically and simultaneously opens switch 31 and closes a switch 47 which connects the motor field 28 directly with the exciter 49 through wires 50, 38, and 29. The motor is now synchronized on the line and is capable of carrying its full load.

With the motor now operating, either or both of the compressors may be connected thereto as by clutches 51, 51' in accordance with the receiver pressure conditions. To control the clutch 51, which herein is of the magnetic type, but which may be of any power operated type, there is connected across the field a circuit including wire 52, switch 53, which is opened when the clutch is disengaged, wire 54, slip rings 55 for the clutch magnet and wires 56 and 57 leading back to wire 38. There is also disposed in parallel with the clutch circuit a water valve solenoid 58 for controlling the compressor cooling water valve 59. The solenoid 58 is connected on that side of switch 53 whereby upon closure of the switch the water valve is opened simultaneously upon connection of clutch 51 and conversely is closed upon disconnection of the clutch.

To control switch 53 and effect other desired controlling functions such for instance as operating the clutch, with the compressor unloaded, and subsequently actuating the unloader mechanism so as to load the compressor, or allowing the connected compressor to idle for a predetermined time before disconnecting the clutch and also permitting the motor to continuously operate even after the compressor is disconnected, there is provided a main control circuit including parallel control leads 60 and 61 connected respectively to the main lines L_2 and L_1 . However, before the main control circuit can be operative a switch 62 in line 60 must first be closed, and it is desired that this switch shall not be closed until the motor is fully synchronized, thereby avoiding the possibility of effecting any control, which might otherwise be the case due to the main control circuit being supplied with current from the main line leads. Closure of switch 62 is effected by having its solenoid placed in parallel, as by wires 63, across the field or clutch circuit wires 52 and 57. It is thus seen that switch 62 will only be closed when the field 28 is connected to the exciter, at which time the motor 1 is synchronized. With switch 62, manually operable cutout switch 64 and a normally closed switch 64a, which is operated in accordance with certain temperature relay devices to be described, all closed, the main control functions may now be effected in accordance with the receiver pressure conditions.

To effect the control in accordance with this pressure, switch 65 is operated by a dia-

phragm or other suitable mechanism connected preferably directly to the compressor receiver R, thereby being responsive to the compressor discharge pressure. This diaphragm and switch are, for purposes of illustration, arranged to close when the receiver pressure is at, say, 95 pounds and to open when the receiver pressure is at, say 98 pounds. Assuming that the pressure is above 98 pounds, switch 65 is opened; as is likewise the case with switch 53; wherefore the clutch will be disconnected. However if the receiver pressure should drop to or below 95 pounds, switch 65 will close, whereupon current flows from wire 60 through wire 66, switch 65 and thence divides between parallel wires 67 and 68 to pass through a time relay 69 and a solenoid 70 back to the other control lead 61. The sequence of operation now desired is to first connect the compressor of unit A in unloaded condition to the driving motor and after a predetermined interval of time to then load the compressor. This is effected in that upon energization of coil 70 switch 71 is opened, thereby preventing any current from flowing between control leads 60 and 61 as by way of wires 72, 73 and a second time relay 74. This relay has its switch 75 normally maintained closed whereby current can flow between the control leads 60, 61 as by way of wires 76, solenoid 77, and switch 75, thereby energizing solenoid 77 and effecting closure of the clutch and water control valve switch 53. The clutch 35 will thus be energized or otherwise suitably actuated so as to connect the unloaded compressor to the synchronous motor, and likewise the water valve 59 is opened. To load the compressor, time relay 69 is set to close its switch 78 at a relatively short interval of time after closure of switch 65, which is simultaneous with connection of clutch 51. This time interval for relay 69 is, for purposes of illustration, herein considered to be nine seconds. Upon closure of switch 78 current then flows between control leads 60, 61 as by way of wire 79, switch 78 and wire 80 to energize the unloader solenoid 81 thereby to load the compressor, this solenoid indicating diagrammatically any desired or usual type of unloader valve mechanism. The compressor will now pump up receiver pressure until it reaches 98 pounds, when switch 65 is opened, thereby breaking the circuit through time relay 69 and solenoid 70, whereupon switch 78 opens and switch 71 closes by gravity or by a spring if such is desired. Closure of switch 71 thereupon permits current to flow between the control leads as by wires 72, 73 to start operation of the time relay 74, which is adapted to open a switch 75 after, say, a five minute interval of time. With the switch 75 remaining closed, clutch control solenoid 77 is maintained energized and accordingly switch 53 kept closed, thereby

causing the compressor to continue being driven even though it is unloaded. If the receiver pressure does not fall to 95 pounds before the expiration of the five minute period as controlled by the time relay 74, switch 75 will thereupon be opened to deenergize solenoid 77 and accordingly open switch 53 to likewise deenergize or so control the clutch 51 as to disconnect the compressor from the synchronous motor, while yet permitting the synchronous motor to continue operation. When the pressure falls to 95 pounds the above cycle of operations is repeated by closure of switch 65.

In case the temperature of the compressor bearings should become excessive or if, due to some other compressor trouble, the compressor-discharged air becomes excessively heated, switch 64a is opened, thereby breaking the current flow through the main control lead 60 and thus disconnecting the compressor and preventing any further operation thereof although permitting motor operation to continue. This is accomplished by the provision of a plurality of thermostatically operated switches 82, one adapted for each of the compressor bearings, while a similar relay switch 83 is provided to be responsive to the temperature of the compressor discharge fluid, these relay switches 82 being placed in series in a line 84 connected to line L₁ and passing through solenoid of switch 64a and thence back through line 60 to line L₂. It is thus seen that when the solenoid of switch 64a is deenergized due to opening of any switch 82 or 83, switch 64a will open, for instance by gravity or due to a spring, thereby opening the control lead 60. It is also seen that once the switch 64a is opened it can be only manually reclosed due to the fact that even though the compressor bearings should cool down sufficiently to permit reclosure of their relay switches 82, or should the discharge pressure fluid likewise cool so that switch 83 closes, still the solenoid for switch 64a cannot be energized as there is no connected line leading back to the main line wire L₂. The operator is thus compelled to manually close switch 64a and thus be reminded that the equipment should be inspected due to the presence of trouble.

With the main compressor control circuit broken, the synchronous motor as before stated will continue to operate, but if for any reason the motor bearings should heat excessively, either or both of the thermostatically operated motor bearing relay switches 17 will open, thereby deenergizing solenoid 18, whereby switch 19 will open by gravity or by a spring if desired, thus deenergizing the solenoid 25 to permit reopening of main line switch 26 in any manner usual with switches suitable for main line circuits. The motor is thus stopped, thereby shutting down

the whole installation irrespective of the operating conditions of the two units.

Inasmuch as the compressor control circuit, and elements controlled thereby, for unit B are identical in every respect with the control circuit described for unit A, with the exception that the pressure switch 65' is adjusted to close at 97 pounds and open at 100 pounds, the corresponding wires and elements of the controls for units A and B are given the same reference numbers but with primes indicating unit B.

The dual operation of the two units is as follows. After the compressor for unit A is disconnected from the motor due to the receiver pressure building up to 98 pounds, the compressor for unit B continues to pump until the receiver pressure reaches 100 pounds, whereupon switch 61' opens, thereby unloading the compressor and disconnecting its clutch in the same manner as with unit A. When the receiver pressure drops to 97 pounds, switch 65' closes, thereupon bringing compressor of unit B into action; but if the receiver pressure continues to drop to 95 pounds even while unit B is pumping, switch 65' closes, thereupon bringing the compressor for unit A into service, the two units together then pumping up the receiver pressure until it reaches 98 pounds, when unit A is disconnected, whereupon unit B continues pumping until the receiver pressure reaches 100 pounds, and then it also is disconnected.

When it is desired to completely shut down the installation, including the synchronous motor, the operator merely presses the normally closed push button switch 12 to momentarily break the circuit from wire 3 through contact arm 10 and thereby deenergize solenoid 18 to open the circuit including wires 23 and 24 of the main switch solenoid 25.

It is thus seen that my improved arrangement is adapted to permit continuous operation of the synchronous motor once it is started, while the compressors are operated only in accordance with the demand for fluid pressure thereby permitting economical operation of the compressors and also improving the power factor or maintaining a high power factor by the continuous operation of the synchronous motor. In case one or the other or both of the motor bearings should become excessively heated, the corresponding thermostatically operated motor bearing relays 17 will open, thereby shutting down the complete plant. However, should compressor bearing trouble occur, or compressor trouble causing the discharge air to heat, the clutch will be deenergized and that unit having the trouble will come to rest without interfering with the operation of the motor or the other unit. It is also seen that by the use of the manually operable stop switch 64, 64', either one or both compressor units may be discontinued at the will of the operator. The

equipment also is rendered as nearly fool-proof as possible by the provision of the solenoid operated contactor 62 placed in series with the main control circuit lead 60 and energized by being placed in parallel with the motor field circuit, thereby insuring that the motor is up to speed and that the field is applied to the motor before there is any possibility of loading the motor, as by connecting either of the magnetic clutches.

While there is in this application specifically described one form which this invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. The combination comprising a continuously operating motor, a mechanism driven thereby, means for connecting said motor and mechanism in driving relation or disconnecting them, and means for automatically disconnecting said driving relation in accordance with predetermined conditions of operation while permitting motor operation to continue, said means including a time delay relay adapted to break the driving relation after said predetermined condition of operation has existed for a given interval of time.

2. The combination comprising a continuously operating motor, a mechanism driven thereby, means for connecting said motor and mechanism in driving relation or disconnecting them, and means for automatically disconnecting said driving relation in accordance with the predetermined conditions of operation while permitting motor operation to continue, said means including temperature responsive elements, and an electrical circuit controlled thereby adapted upon occurrence of a predetermined temperature condition to disconnect said driving relation while permitting motor operation to continue.

3. The combination comprising a continuously operating motor, a mechanism driven thereby, means for connecting said motor and mechanism in driving relation or disconnecting them, and means for automatically disconnecting said driving relation in accordance with the predetermined conditions of operation while permitting motor operation to continue, said means including a temperature responsive device and an electrical circuit controlled thereby whereby upon occurrence of a predetermined temperature, said motor and driven mechanism are both shut down.

4. The combination comprising a motor, a plurality of mechanisms driven thereby, means for connecting either or both of said mechanisms to said motor or for disconnecting either or both of them from said motor, and

means adapted automatically upon occurrence of predetermined operating conditions to disconnect either or both of said mechanisms so that they may stop while permitting motor operation to continue.

5. The combination comprising a motor, a plurality of pumping mechanisms driven thereby, means for connecting either or both of said mechanisms to said motor or for disconnecting either or both of them from said motor, and means adapted automatically upon occurrence of predetermined operating conditions to disconnect either or both of said mechanisms so that they may stop while permitting motor operation to continue.

6. The combination comprising a motor, a plurality of pumping mechanisms driven thereby, means for connecting either or both of said mechanisms to said motor or for disconnecting either or both of them from said motor, and means adapted automatically upon occurrence of predetermined pressure conditions under which the compressors operate, to disconnect either or both of said mechanisms so that they may stop while permitting motor operation to continue.

7. The combination comprising an electric motor, a compressor having load controlling means, a power operated clutch mechanism for connecting said compressor and motor in driving relation, means for automatically disconnecting said clutch and allowing said compressor to stop when the compressor discharge pressure is at a predetermined value while allowing motor operation to continue, and means whereby when the discharge pressure is at another predetermined value the clutch mechanism is reconnected while said compressor is in unloaded condition.

40 8. The combination comprising an electric motor, a compressor having load controlling means, a clutch mechanism for connecting said compressor and motor in driving relation, means for automatically disconnecting said clutch and allowing said compressor to stop when the compressor discharge pressure is at a predetermined value while allowing motor operation to continue, means whereby when the discharge pressure is at another predetermined value the clutch mechanism is reconnected while said compressor is in unloaded condition, and means for loading the compressor after the clutch has been connected for a predetermined interval of time.

9. The combination comprising a synchronous motor, a plurality of compressors, clutches adapted to connect said motor and compressors in driving relation, and means including a control circuit whereby said clutches are adapted to connect the compressors to the motor only after the motor has been synchronized.

10. The combination comprising a synchronous motor, a compressor, a fluid pres-

sure receiver therefor, a clutch for connecting said compressor in driving relation to said motor, a control circuit for said clutch, a switch in series with said control circuit adapted to be closed only when the motor has been synchronized, and means adapted upon closure of said switch and when the receiver pressure is at a predetermined value to effect connection of said clutch, and to effect disconnection of the clutch when receiver pressure is at another predetermined value, said control circuit being so arranged that when the clutch is disconnected the motor is adapted to continue operation.

11. The combination comprising a motor, a mechanism driven thereby, means for connecting said mechanism to said motor or disconnecting it therefrom while said motor continues to operate, means for automatically effecting operation of said first mentioned means to effect disconnection upon the occurrence of predetermined conditions of operation of said driven mechanism, and means also automatically operative but controlled by the operating conditions of said motor for stopping the latter.

12. In combination, a driving motor, a pump driven thereby, means for establishing or interrupting a driving connection between said motor and pump, means for automatically controlling said first mentioned means to effect interruption of the driving connection when the discharge pressure of said pump reaches and is maintained for a predetermined time at a predetermined value, and means controlled by temperatures which rise during pumping operation for also automatically controlling said first mentioned means to interrupt the driving connection upon the occurrence of excessive temperatures.

13. In combination, a motor, a pump driven thereby and having load controlling mechanism, means for controlling the driving connection between said motor and pump, means operative automatically upon the attainment of a predetermined pump discharge pressure for effecting unloading of said compressor through said load controlling mechanism and, after unloaded operation for a predetermined time, to interrupt the driving connection between the pump and motor while said motor continues to operate.

14. In combination, a motor, a pump, means for operatively connecting said pump to said motor for drive thereby and for disconnecting said pump from said motor, means for loading said pump, a pump discharge pressure controlled device, said device controlling said pump loading means and having associated therewith a time delay apparatus delaying loading on attainment of a predetermined minimum pressure, and means including a time delay mechanism also controlled by said device for effecting disconnecting operation.

of said first mentioned means when said pump operates unloaded for a predetermined time.

15. In combination, a motor, pumping mechanism driven thereby, pump discharge pressure controlled means for effecting unloading of said pumping mechanism upon the attainment of a predetermined compressor discharge pressure, mechanism for automatically disconnecting said pumping mechanism 10 from said motor operative only substantially after unloading thereof, means for cooling said pumping mechanism, and controlling means for said cooling means operable with said last mentioned mechanism.

15 16. The combination comprising a motor, a plurality of mechanisms driven thereby, means for connecting either or both of said mechanisms to said motor or disconnecting either or both therefrom, and means adapted 20 automatically upon occurrence of predetermined operating conditions to unload, or both to unload and disconnect, either or both of said mechanisms so that they may stop while permitting motor operation to 25 continue.

17. The combination comprising a motor, a plurality of pumping mechanisms driven thereby, means for connecting either or both of said mechanisms to said motor or disconnecting either or both therefrom, and means adapted automatically upon occurrence of predetermined operating conditions to unload, or both to unload and disconnect, either or both of said mechanisms so that they may stop while permitting motor operation to 35 continue.

18. The combination comprising a motor, a plurality of mechanisms driven thereby, means for connecting either or both of said 40 mechanisms to said motor or disconnecting either or both therefrom, and means adapted automatically upon occurrence of predetermined operating conditions to unload, or disconnect, or both to unload and disconnect, either or both of said mechanisms so that they may stop while permitting motor operation to 45 continue.

19. The combination comprising a motor, a plurality of pumping mechanisms driven 50 thereby, means for connecting either or both of said mechanisms to said motor or disconnecting either or both therefrom, and means adapted automatically upon occurrence of predetermined operating conditions to unload, or disconnect, or both to unload and disconnect, either or both of said mechanisms so that they may stop while permitting motor operation to 55 continue.

20. The combination comprising a motor, 60 a plurality of pumping mechanisms driven thereby, means for connecting either or both of said mechanisms to said motor or disconnecting either or both therefrom, and means adapted automatically upon occurrence of 65 predetermined pressure conditions under

which the compressors operate, to unload, or both to unload and disconnect, either or both of said mechanisms so that they may stop while permitting motor operation to continue.

In testimony whereof I affix my signature.

WILLIAM EARL HUGHES.
